CLAIM

The ornamental design for an outrigger for scaffold substantially as shown and described.

DESCRIPTION

FIG. 1 is a perspective view of an outrigger for scaffold according to the design showing the outrigger in an open state;

FIG. 2 is a front elevational view of the outrigger for scaffold of FIG. 1;

FIG. 3 is a rear elevational view of the outrigger for scaffold of FIG. 1;

FIG. 4 is a right side elevational view of the outrigger for scaffold of FIG. 1;

FIG. 5 is a left side elevational view of the outrigger for scaffold of FIG. 1;

FIG. 6 is a top plan view of the outrigger for scaffold of FIG. 1;

FIG. 7 is a bottom plan view of the outrigger for scaffold of FIG. 1;

FIG. 8 is a perspective view of the outrigger for scaffold of FIG. 1 showing the outrigger in a closed state;

FIG. 9 is a front elevational view of the scaffolding of FIG. 8;

FIG. 10 is a rear elevational view of the scaffolding of FIG. 8;

FIG. 11 is a right side elevational view of the outrigger for scaffold of FIG. 8;

FIG. 12 is a left side elevational view of the outrigger for scaffold of FIG. 8;

FIG. 13 is a top plan view of the outrigger for scaffold of FIG. 8;

FIG. 14 is a bottom plan view of the outrigger for scaffold of FIG. 8;

FIG. 15 is an environmental view of the outrigger for scaffold of FIG. 1 showing the outrigger in an open state and affixed to a scaffold; and,

FIG. 16 is an enlarged fragmentary view of the environmental view of FIG. 15.

(Continued)

The broken lines are for illustrating portions of the outrigger for scaffold that form no part of the claimed design.
